(57) **CLAIM**

The ornamental design for a grill oven, as shown and described.

DESCRIPTION

FIG. 1 is a top perspective view of a grill oven showing my new design;

FIG. 2 is a bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view taken from circle 9 in FIG. 1; and,

FIG. 10 is an enlarged view taken from circle 10 in FIG. 3. The dash-dot broken lines in the drawings depict the portions of the grill oven that form no part of the claimed design.

The dot-dash broken lines in the drawings depict the boundaries of the enlarged views that form no part of the claimed design.

1 Claim, 10 Drawing Sheets
